MERCHANTISE DISPLAY TABLE

Leslie S. Janes, John G. Raben, and John Nielsen,
Chicago, Ill., assignors to Sears, Roebuck and
Co., Chicago, Ill., a corporation of New York

Application October 29, 1936, Serial No. 108,194

14 Claims. (Cl. 312—140.1)

Our invention relates to store equipment and has to do more particularly with tables and the like which are especially adapted for the display of merchandise.

Tables and the like which have heretofore been used for this purpose are either of limited capacity or, where the capacity is relatively large, much of the space has been available only for storage and not for display.

10 A particular object of our invention is to provide a table which will have an exceptionally large amount of space available for display, so that said device may function to a maximum extent as a selling aid, in contradistinction to a mere storage device.

Another object is to provide an article of the type referred to which may be fabricated from standard parts and may be quickly converted, with ordinary tools, into a large number of different designs, giving various esthetic effects and rendering the device available for different purposes.

20 A further object is to provide a device of the type referred to which will be of simple and sturdy construction, attractive in appearance, economical to fabricate, and generally satisfactory for the purposes desired.

We have devised a construction of table, which may be fabricated from sheet metal, having 30 cantilever extensions capable of supporting and displaying large quantities of merchandise, and constructible in standard sections.

Referring now to the drawings forming a part of this specification and illustrating certain preferred embodiments of our invention:

35 Fig. 1 is a perspective view of one embodiment of our invention;

Fig. 2 is a perspective view of another embodiment of our invention;

40 Fig. 3 is a plan view of the top of the article shown in Fig. 1;

Fig. 4 is a sectional view taken substantially along the line 4—4 of Fig. 1;

Fig. 5 is a sectional view taken substantially 45 along the line 5—5 of Fig. 1;

Fig. 6 is a sectional view taken substantially along the line 6—6 of Fig. 5;

Fig. 7 is a sectional view taken substantially 50 along the line 7—7 of Fig. 1; and

Fig. 8 is a sectional view taken substantially along the line 8—8 of Fig. 1.

In our preferred construction, tables embodying our invention are fabricated out of sheet metal. Such material is available at relatively 55 low cost, lends itself readily to modern methods

of fabrication, is especially adaptable to "modern" styling, and is sufficiently strong to meet the requirements of any normal load that is likely to be required for ordinary merchandise. Furthermore, such material is easily cleaned.

5 The embodiment shown in Fig. 1 comprises shelf sections 10a 10b, and 10c. Said sections may be formed of sheet metal, and preferably have an integral rim portion 12 which may be rectangular in cross section, as seen in Fig. 4.

10 Extending longitudinally of each of the tray or shelf portions 10a and 10b is a plurality of channel shaped stiffening or reinforcing members 15 which may be conveniently stamped out of sheet metal. Said stiffening members have 15 outwardly extending marginal flanges 16 which may be attached to the shelf sections as by spot welding. This method of reinforcement, which may be referred to as pan bracing, is used substantially throughout.

20 Also extending longitudinally of the marginal portions of the shelf sections are L-shaped anchor plates 18, said plates being secured as by spot welding to the underside of said shelf sections and having a leg 18a disposed adjacent and 25 spot welded to the inside of rim portion 12. Said anchor plates have spaced countersunk perforations 19 receiving securing members such as flat headed screws 20 for the attachment of angle braces 22, said braces being spot welded to spacing panels 25. The screws 20 are welded to the anchor plates 18 before the latter are welded in place. The angle braces 22 are provided with 30 bent flanges 23 which dig into the underside of the anchor plates 18 to make a stiff joint. After 35 assembly of angle braces 22 on screws 20 they are retained by means of nuts 24.

The spacing members 25 are channel shaped in cross section as seen best in Fig. 1, having a web portion 26, leg or column portions 27, the latter having inturned portions 28, the latter adding greatly to the strength of the spacers in supporting heavy loads of goods on the trays. The spacers are apertured as at 30 to permit passage of the stiffening channels 15, and are themselves provided with stiffening pan braces 15'.

45 As seen in Fig. 8, the intermediate tray or shelf 10b is secured between spacers 25 at the top and bottom thereof and the assembly is secured by means of angle braces 22 similar to the braces 22 shown in Fig. 4, said members being bolted together in opposed relation by means of the bolt 32 and nut 33. It will be seen that we have provided a very secure joint by means of the bracing of the flanges 23 of the angle braces 50 55

22 on opposite sides of the tray 10b as well as the bracing of said angle members and spacers 25 against the rim 12 of the tray.

As seen in Figs. 1, 5 and 7, the lowermost tray 5 10c rests on a channel shaped base 35, said base having slide domes 37 secured to the corners. The base is reinforced by Z-members 38 at spaced points.

Panels 40 are disposed between shelves 10b and 10c at each end of the table, said panels preferably having round corners conforming with the corners of the tray or shelf members and having inwardly extending flanges 42 at each end thereof. Thus, these end panels are substantially 15 similar to the spacers 25 and constitute very effective supports for any normal load which may be placed on the tray 10b. At their upper portion the end panels 40 (Fig. 5) are provided with inwardly extending flanges 43 which may be 20 bolted as at 44 to the return flange 45 of the rim portion 12. Rear panels 46 may be provided between the end panels 40 and spacers 25, said rear panels being provided with inturned flanges 47 bolted to the flanges 42 of the end panels as at 48. Rear panels may likewise be provided between the spacers 25 and similarly secured. These rear panels may be stiffened by pan braces 15.

At the bottom of the panels 40, they are secured 30 as by spot welding to corner brackets 50. Said brackets have upstanding flanges 51, 51' welded to the end panel on opposite sides of the corner, a downwardly extending flange 52, and a horizontal portion 53 through which extends a screw 35 55. Said screws connect the end panels through brackets 50 to the tray 10c and also to the base 35.

The base 35 has an inwardly extending flange 57 which receives the screw 55 and also a flange 58 to which are secured the corner slide domes 37.

40 It will be seen that we have provided a display table which is simple in construction and relatively inexpensive, although very strong, by reason of its sheet metal fabrication, and having all of its shelf space available for display. It will 45 also be apparent that by reason of the fact that our device is formed by the assembly of more or less standard parts bolted together, it may be modified by the purchaser within considerable 50 limits to meet various requirements and give different effects. Thus, for example, the end and rear panels may be removed, the number of trays 55 may be increased or diminished, the spacing of the spacers may be modified, a large number of bolt holes being provided for that purpose in the various trays, and various other modifications may be made. Obviously, such an arrangement provides a very flexible unit for the merchandiser.

Fig. 2 shows a modification which is substantially similar in construction to the embodiment 60 just described except that it provides a pair of cantilever extension shelves 65, 65, and 66, 66 at each end, the end panels being omitted, giving a true cantilever construction of the shelves. This embodiment, therefore, gives added display 65 value.

Various modifications coming within the spirit 70 of our invention may suggest themselves to those skilled in the art, and hence we do not wish to be limited to the specific forms shown or uses mentioned, except to the extent indicated by the appended claims, which are to be interpreted as broadly as the state of the art will permit.

We claim:

1. A merchandise display table formed of sheet 75 metal, said table having a pair of shelves, verti-

cally extending horizontally spaced panels disposed between said shelves and spaced inwardly from the ends thereof; whereby the ends of said shelves are free in cantilever style, said panels having angle members forming bracing means disposed at substantially right angles from the ends thereof, one leg of an angle member being parallel with the panel, the space between said shelves being substantially free except for said panels.

2. A merchandise display table formed of sheet metal, said table having a pair of shelves, vertically extending horizontally spaced panels disposed between said shelves, said panels having angle members forming bracing means disposed at substantially right angles from the ends thereof, one leg of an angle member being parallel 15 with the panel, the space between said shelves being substantially free except for said panels, means supporting said shelves in elevated relation to a floor, and means connecting said parts and providing quick demountability thereof.

3. A merchandise display table formed of sheet metal and comprising a plurality of shelves and 25 spacing members disposed therebetween and inwardly of the ends thereof, said spacing members having channel shaped ends, the space between said shelves being substantially free at the extremities thereof and between said extremities and said spacing members.

4. In sheet metal furniture, a shelf member having an integral rim consisting of an upwardly extending flange, a downwardly extending flange and an inwardly extending return flange, a vertical panel disposed in position to be clamped to 35 said rim, and detachable means clamping said panel to said rim.

5. In sheet metal furniture, a shelf member having an integral rim consisting of an upwardly extending flange, a downwardly extending 40 flange, and an inwardly extending return flange, a vertical panel having a flange disposed in clamping relation to said rim, and detachable means clamping said panel to said rim, said clamping means comprising a screw-secured angular member bearing against said flange.

6. In sheet metal furniture, a shelf member having a rim provided with an upwardly extending flange, a downwardly extending flange, and an inwardly extending return flange, a vertical panel disposed adjacent said rim, and means detachably clamping said panel in position comprising an angular member having a leg bearing against said panel and a leg screwed to said shelf member, the free edge of said last 55 mentioned leg resiliently engaging the surface of said shelf member.

7. In sheet metal furniture, a shelf member having a rim provided with an upwardly extending flange, a downwardly extending flange, 60 and an inwardly extending return flange, a vertical panel having a face disposed adjacent said rim, and detachable means clamping said panel in position.

8. In sheet metal furniture, a shelf member having a rim provided with an upwardly extending flange, a downwardly extending flange, and an inwardly extending return flange, a vertical panel having a flange disposed adjacent said rim, and detachable means clamping said panel in 70 position, said clamping means comprising a screw secured angular member bearing against said flange.

9. In sheet metal furniture, a shelf member having a rim provided with an upwardly extend-

5 ing flange, a downwardly extending flange, and an inwardly extending return flange, a reinforcing member having a leg permanently secured to the lower surface of said shelf and a leg secured in bracing relation to the downwardly extending flange of said rim, a vertical panel disposed adjacent said rim, and means detachably clamping said panel in position comprising an angular member having a leg bearing against 10 said panel and a leg screwed to said reinforcing member, the free edge of said last mentioned leg resiliently engaging the surface of said reinforcing member.

10. In sheet metal furniture, a horizontal 15 goods supporting member having a rim provided with a flange depending below the plane of the horizontal member, a U-shaped panel arranged perpendicularly to said member and having a leg disposed adjacent said flange, and 20 releasable means including an angle member carried by said horizontal member for clamping said leg against said depending flange.

11. In sheet metal furniture, a pair of horizontal goods supporting members, each having a 25 rim comprising an upstanding flange and a depending flange, a pair of spaced members separating said horizontal members, said separating members each being approximately of U-formation, and means carried by the horizontal members 30 releasably clamping a leg of said separating members against a flange of said rim.

12. In sheet metal furniture, a pair of horizontal goods supporting members, each having a rim comprising an upstanding flange and a de-

pending flange, a pair of spaced vertical panels separating said horizontal members, said panels each being approximately of U-formation, and means carried by the horizontal members releasably clamping a leg of said panels against a flange of said rim, said panels being spaced inwardly of the ends of said horizontal members so that the spaces between said panels and between the latter and the ends of said horizontal members are substantially clear.

13. In sheet metal furniture, a horizontal goods supporting member having a rim provided with an upwardly extending flange and a downwardly extending flange, substantially U-shaped coplanar panels extending perpendicularly on opposite sides of said horizontal member and spaced inwardly from an end thereof, means releasably securing said panels to said member comprising clamps engaging a corresponding leg of each panel, and common means 20 attaching said clamps to said horizontal member.

14. A merchandise display table formed of sheet metal, said table having a pair of shelves, vertically extending horizontally spaced panels 25 disposed between said shelves and spaced inwardly from the ends thereof, whereby the ends of said shelves are free in cantilever style, said panels having their extremities deformed to provide substantially U-shaped bracing portions.
